HOLDER FOR A TOOTHPASTE TUBE OR THE LIKE

Elizabeth Ann Kirk, 492 S. Williams St., Denver, Colo.

Filed June 20, 1960, Ser. No. 61,042

Term of patent 7 years

(Cl. D4—3)

Fig. -1

Fig. -2

Fig. -3

FIG. 1 is a left side elevational view of a holder for a toothpaste tube or the like embodying my design;

FIG. 2 is an enlarged top plan view thereof; and

FIG. 3 is an enlarged front perspective view taken from the top and right side thereof.

The characteristic features of my design for the holder disclosed reside in the tube support having the configuration shown.

I claim:

The ornamental design for a holder for a toothpaste tube or the like, as shown and described.
